UNITED STATES PATENT OFFICE

166,312

SAFETY LIGHT

Raymond T. Holland, Macon, Mo.

Application April 28, 1949, Serial No. 2,314

Term of patent 3½ years

(Cl. D48—32)

To all whom it may concern:

Be it known that I, Raymond T. Holland, a citizen of the United States of America, residing at Macon, in the county of Macon and State of Missouri, have invented a new, original, and ornamental Design for a Safety Light, of which the following is a specification, reference being had to the accompanying drawing, forming part thereof.

Figure 1 is a perspective view of a safety light, showing my new design.

Fig. 2 is a bottom plan view.

Fig. 3 is a front elevational view.

Fig. 4 is a vertical sectional view on line 4—4 of Fig. 1.

Fig. 5 is a sectional view on line 5—5 of Fig. 4.

The dominant features of this design reside in the bracket.

I claim:

The ornamental design for a safety light, as shown and described.

RAYMOND T. HOLLAND.
